UNITED STATES PATENT OFFICE.

JOHN STEPHENSON, OF NEW YORK, N. Y.

DESIGN FOR A LAMP-BOX FOR RAILROAD-CARS.

Specification forming part of Design No. 1,959, dated June 14, 1864.

To all whom it may concern:

Be it known that I, JOHN STEPHENSON, of the city, county, and State of New York, have invented or produced a new and original Design for a Lamp-Box for Railroad-Cars; and I do hereby declare that the following is a full, clear, and exact description of the same, reference being had to the accompanying drawings, making a part of this specification, in which—

Figure 1 is a front view of a lamp-box constructed according to my design; Fig. 2, a horizontal section of the same, taken in the line $x x$, Fig. 1.

Similar letters of reference indicate like parts.

This invention relates to a new and original design for a lamp-box such as are placed in the corners of city or horse railroad cars, near the roofs, to receive a lamp.

The box A is of rectangular form in its horizontal section, and it is provided with a roof or top having a double pitch, $a a$, one side of the top corresponding to the pitch of the roof p of the car.

B is the glass door at the front of the lamp-box, the bottom and side pieces c of the frame of said door forming three sides of a quadrangle, and the top piece c' being slightly arched or curved, as shown in Fig. 1, the under surface of the cap-piece d , above c' , and against which c' abuts, being hollowed out or curved, corresponding to c' .

E is the chimney-cap, placed centrally on the top of the lamp-box, and having an enlarged lower part, f , on which a top part, g , of smaller diameter is placed, the part g being provided with a conical hood or top piece, h , and the top of the lower part, f , provided with pitched roof i , extending from g to a short distance beyond the side of f , as shown in Fig. 1.

I claim as new and desire to secure by Letters Patent—

The configuration of the several parts herein shown and described, to form a new and original design for a lamp-box for railroad-cars.

JOHN STEPHENSON.
